Waco, Tex. 76701

Filed May 8, 1970, Ser. No. 22,898

Term of patent 14 years

Int. Cl. D29—99

U.S. Cl. D72—1

Fig. 1.

Fig. 2.

FIG. 1 is a front elevational view of a warning sign showing my new design, the rear being plain and unornamented; and

FIG. 2 is a side elevational view thereof.

The characteristic features of my design reside in the specific appearance of the surface ornamentation on the front face of the sign, which ornamentation is shaded to indicate contrast as well as color. The indicia and stand-ard are shown in broken lines for illustrative purposes only.

I claim:

The ornamental design for a warning sign, as shown and described.
